[57] CLAIM

The ornamental design for a combined clock, timer and schedule manager, as shown and described.

DESCRIPTION

FIG. 1 is a top, front and right side perspective view of a combined clock, timer and schedule manager showing our new design;

FIG. 2 is a front elevational view;

FIG. 3 is a rear elevational view;

FIG. 4 is a top plan view;

FIG. 5 is a bottom plan view;

FIG. 6 is a left side elevational view;

FIG. 7 is a right side elevational view;

FIG. 8 is a top, front and right side perspective view, shown in an alternate condition of use; and,
FIG. 9 is a top, front and right side perspective view thereof, the broken line showing of a support bar and speaker are environmental only and form no part of the claimed design.

FIGS. 1, 8 and 9 have been drawn on a reduced scale with respect to FIGS. 2-7.

FIG. 1

FIG. 2

FIG. 3

FIG. 4

FIG. 5

FIG. 6

FIG. 7

FIG. 8

FIG. 9

UNITED STATES PATENT AND TRADEMARK OFFICE
CERTIFICATE OF CORRECTION

PATENT NO. : Des. 331,018
DATED : November 17, 1992
INVENTOR(S) : Kenji Watanabe, et. al.

It is certified that error appears in the above-indentified patent and that said Letters Patent is hereby corrected as shown below:

On the Title page, item [73], Assignee: should be "King Jim Co., Ltd".

Signed and Sealed this

Second Day of August, 1994

Attest:

BRUCE LEHMAN

Attesting Officer

Commissioner of Patents and Trademarks
